APPARATUS FOR THE PRODUCTION OF ELECTROLYTIC TINPLATE

BACKGROUND OF THE INVENTION

The present invention relates to improved apparatus for the production of electrolytic tinplate.

It is common practice at the present time to manufacture tinplate continuously by passing what is in effect an endless strip of steel through various processing zones. The steel strip, which may be anything up to about 45 inches wide, is passed first through an uncoiling zone, then through a preparation zone in which it is cleaned by both chemical and mechanical processes, then through an electrolytic plating zone in which it is passed through several electrolytic baths, then through the finishing zone in which it is rinsed and otherwise finished and finally into a recoiling or shearing and stacking zone.

The present invention is concerned more particularly with the apparatus used in the plating zone. In this zone the steel strip passes over a first roll, known as a conductor roll, whence it passes vertically downwards through a first electrolytic bath at the bottom of which is a first turning or sink roll, from which the strip passes vertically upwards out of the liquid of the bath, over a second conductor roll, vertically downwards into a second bath, around a second turning or sink roll at the bottom of the second bath, vertically upwards to a third conductor roll, and so on through any number of electrolytic baths. The electrolyte in each bath may be acidic in nature and hence highly corrosive and is maintained at a temperature of up to 200° F. The strip passes through the several baths at a speed which may be as high as 1,500 feet per minute or more and as it snakes its way up and down through the several baths and around the conductor and sink rolls, each limb of each loop must be kept in an accurately vertical constant path, since it passes between vertical anodes arranged one on each side of each limb of each loop.

In order that the distance between the strip and the anodes on either side of it can be maintained and the anodes on either side of it can be maintained constant, the strip is maintained under tension throughout its whole passage through the baths.

The steel strip itself serves as a conductor while it is in the bath and current flows through the strip and conductor roll. For the passage of current to be satisfactory, the contact between the strip and the conductor roll must be uniform and tight. Thus there must be no specks of dirt between the strip and conductor roll, nor must there be pits in either surface, since, if there were, arcing would occur at these points of irregularity and the arcing would give rise to imperfect plating.

It will be seen therefore that each conductor roll has to satisfy the following stringent conditions:

1. It must be resistant to the corrosive action of the acid bath, since the strip carries the acid up on to the upper conductor rolls.
2. The rolls have to carry a heavy current.
3. The rolls must be accurately cylindrical and highly polished in order to maintain a perfect contact with the strip.
4. Each roll has to support the tension in two limbs.
5. It must generally operate at an elevated temperature.

These are not by any means all the conditions which must be satisfied by each conductor roll, but they are sufficient to show that these rolls perform an important function in the process. Because of the many conditions, the rolls are expensive to manufacture.

Such conductor rolls may also be used at other sections of the line, for example in the cleaning and pickling section, the chemical treatment section and in the reflow section.

Hitherto, each roll has consisted of a steel shaft carrying a cylindrical steel barrel which in turn bears a shrunk-on jacket of wrought copper. The barrel is hollow so that it may be water cooled and is made of steel to support the tensions in the strip. Copper is used for the jacket, about $\frac{1}{2}$ to $1 \frac{1}{2}$ inches thick, so that the current may be carried satisfactorily and

because copper can easily be machined and will take a high finish.

It is, however, extremely difficult to coat the steel barrel with a $\frac{1}{2}$ inch layer of copper, mainly because of the large size of the barrel, which may be about 18 inches to 24 inches in diameter and about 4 feet in axial length.

The barrel is supported on the shaft with the aid of a pair of annular spacers located at the ends of the barrel and lying between the barrel and shaft. The ends of the shaft protrude from the barrel, through the spacers, serve as bearings for the roll, and serve as current collectors.

The whole of the barrel and protruding ends of the steel shaft need to be coated with copper. Hitherto, this has been done by forming forged and/or rolled copper end jackets and a cylindrical barrel jacket, all of which are secured over their respective portions of the roll. Both the end forged jacket portions and the cylindrical barrel portion of the jacket are difficult to obtain. They are expensive to purchase and can be obtained only after a waiting period of months. When they have been obtained, the process of fitting them on to the steel roll and then welding them together is also expensive and time consuming. When this has been done, the barrel portion of the welded jacket is ground to accurate dimensions and then coated with a thin layer of chromium which is finally polished to give the necessary good contact surface. When such jacketed rolls need repair, the cost may be as much, or more, than that of making a new roll.

Nevertheless, such conductor rolls operate fairly satisfactorily; their main disadvantage being that they are expensive and take a long time to make.

It is an object of the present invention to provide an equivalent roll which can be made more cheaply and more easily.

SUMMARY OF THE INVENTION

According to the present invention, there is provided a conductor roll comprising a coaxial assembly of shaft, cylindrical barrel and pair of annular spacers, the spacers being located at the ends of the barrel so as to hold the latter spaced over a central body portion of the shaft with the ends of the shaft protruding from the barrel, characterized in that at least the barrel part of the assembly is coated externally with an arc-sprayed main coating consisting of copper, stainless steel or monel metal.

According to a further feature of the invention there is provided a conductor roll comprising a coaxial assembly of shaft, cylindrical barrel and pair of annular spacers, the spacers being located at the ends of the barrel so as to hold the latter spaced over a central body portion of the shaft with the ends of the shaft protruding from the barrel, characterized by the combination of features that the barrel part of the assembly is coated externally with an arc-sprayed main coating of copper and the ends of the shaft protruding from the barrel are each fitted with a wrought copper sleeve.

According to yet another feature of the invention there is provided a method of making an electrically conductive roll which is in the form of a coaxial assembly of shaft, cylindrical barrel and pair of annular spacers, the spacers being located at the ends of the barrel so as to hold the latter spaced over a central body portion of the shaft with the ends of the shaft protruding from the barrel, characterized by the steps of assembling the parts of the roll and then arc-spraying onto at least the barrel part of the assembled roll a main coating consisting of copper, stainless steel or monel metal.

DRAWINGS

Preferred forms of the invention will now be described with reference to the accompanying drawings in which:

FIG. 1 is an axial section through a conductor roll the whole of which is arc sprayed with copper,

FIGS. 2 and 3 are, respectively, similar sections through two rolls, portions only of which are arc-sprayed, and

FIG. 4 is a sectional view of a fragment of the steel barrel having successive coatings of aluminum bronze, and copper.

PREFERRED EMBODIMENTS

The roll illustrated in FIG. 1 consists of a coaxial assembly of steel shaft, barrel and pair of annular spacers. The steel shaft is shown at 10A and has a cylindrical central body portion 10 and ends 11 and 12 of reduced diameter. It is made hollow so that cooling water may be passed through it.

The body portion 10 carries intermediate stiffening annular steel plates 13 and 14 and thicker steel annular spacers 15 and 16. One or both spacers 15 and 16 may be keyed to the shaft as at 18. The center body portion 10 of the shaft carries, with the aid of the spacers, the cylindrical steel barrel 19, and the ends 11, 12 of the shaft and the barrel 19 are all coated with a layer of copper which, over the barrel, is about one-half inch thick.

In carrying out the present invention, instead of making this copper jacket in three or more parts and welding them together, as has been done hitherto, the jacket is arc-sprayed on to the steel, so as to produce a unitary jacket without joints. The barrel portion 20 of the jacket is about one-half inch thick and the end portions 21 and 22 are somewhat thicker.

Preferably the part or parts of the assembly to be coated are first given a precoating of a metal, giving high adherence to the steel. Where the main coating is copper, the precoating may be aluminum bronze which is sprayed on, after which the main coating of copper is sprayed on to the precoating. The required thickness of coating is built up continuously and when the required thickness of copper has been produced, the copper is ground and the barrel portion 20 (and it may be other parts also) plated with stainless steel, monel metal, chromium or nickel, which finally is polished to a high finish. Alternatively these metals may be arc-sprayed onto the copper.

In an alternative embodiment of the invention, illustrated in FIG. 2, only the barrel 19A and the external faces of the spacers 15A and 16A are arc-sprayed, while the ends 11A and 12A of the shaft are covered with wrought copper sleeves 30 and 31. The ends of the shaft require to be subsequently threaded, and this embodiment has the advantage that forged copper will stand threading better than sprayed copper. Nevertheless this embodiment may have the disadvantage of requiring a welded joint between the sprayed and forged metal. In order to avoid such joints, the sleeves may be shrunk onto the ends first and the sprayed metal may then be applied to the barrel and spacers and over the edges of the sleeves, to constitute a single, integral jacket.

In a third embodiment illustrated in FIG. 3 the curved sur-

50

face of the barrel 19B only is sprayed and the ends of the shaft and the external faces of the spacers 15A and 16A are covered with forged copper jackets 33 and 34.

Any known or suitable method may be used for the arc-spraying process.

In one method, those parts of the roll to be sprayed were first roughly threaded so as to provide increased mechanical adhesion of the sprayed particles and, at the same time, increase the surface area available for bonding. All sharp edges were removed. The surfaces were then grit blasted to remove corrosion and dirt and, at the same time, further increase the surface area.

The roll was then set up in a chuck, so that it might be rotated during spraying. All the spraying was done from an electric arc, the molten particles being blown on to the roll with the aid of compressed air to which could be added if desired an inert gas designed to inhibit oxidation.

A prespray, as shown in FIG. 4 consisting of a coating of aluminum bronze was first applied to the surface 19C', since this alloy has a high adhesion to steel and to the subsequently sprayed copper 41. The spraying conditions were chosen such as to give coarse particles of the prespray metal.

A main coating of copper was then arc-sprayed on to the aluminum bronze, the conditions being such as to provide a dense, low-shrink deposit of copper.

The spraying was achieved by traversing the spray gun longitudinally of the roll at an average distance of 6 inches while the roll was rotated at a speed of about 120 surface feet per minute. Where the side faces of the spacers were sprayed, this was done by hand, holding the gun approximately at right angles to these surfaces.

The sprayed surfaces were then machined and, in the case of the barrel, the finishing operations such as plating and grinding carried out.

Further particulars of suitable methods of arc-spraying are to be found in

- a. "Der Maschinenmarkt" Nos. 93 and 94 for 18th Nov. 1960 and 24th Mar. 1961 respectively, and
- b. in the textbook entitled "Metal Spraying and the Flame Deposition of Ceramics and Plastics," by W.E. Ballard, publishers: Chas. Griffin & Co.

What I claim is:

1. A conductor roll comprising a coaxial assembly of a shaft, cylindrical steel barrel, and a pair of annular spacers, the spacers being located at the ends of the barrel so as to hold the latter spaced over a central body portion of the shaft with the ends of the shaft protruding from the barrel, aluminum bronze coating on the outer surface of said barrel, and a coating of copper on said aluminum bronze coating.
